CLAIM

The ornamental design for a packaging container, as shown and described.

DESCRIPTION

FIG. 1 is a top right isometric view of the packaging container of the present invention;

FIG. 2 is a rear isometric view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is an environmental view thereof illustrating the packaging container being utilized to display a gun support device.

The portions of the packaging container illustrated in broken lines form no part of the claimed subject matter.
